UNITED STATES PATENT OFFICE.

HARALD ALBRECHTSEN AND SØREN IVER IVERSEN, OF COPENHAGEN, DENMARK.

GAS-COOKER.

1,393,481.

Specification of Letters Patent. Patented Oct. 11, 1921.

Application filed March 2, 1920. Serial No. 362,661.

To all whom it may concern:

Be it known that we, HARALD ALBRECHTSEN and SØREN IVER IVERSEN, both subjects of the King of Denmark, residing at Copenhagen, in the Kingdom of Denmark, have invented certain new and useful Improvements in Gas-Cookers, of which the following is a specification.

The present invention relates to an arrangement by means of which the distance between the burner of a gas-cooker and the bottom of the pot may be varied according to the size of the flame. This object is obtained by the burner being fitted with a telescoping burner-tube, of which one member can be raised or lowered until the proper distance between the flame and pot is found.

In the accompanying drawing the invention forming the subject matter of the present application has been shown in an embodiment by way of example.

Figure 1 is a vertical section through an embodiment of a gas-cooker with an adjustable burner.

Fig. 2 is a top view of the gas-cooker shown in Fig. 1.

In the body *a* of the gas-cooker is disposed the gas-pipe *c* to which is attached at its inner end the burner-tube *d*. On said burner-tube *d* is fitted a tube *e* shiftable thereon and carrying at its upper end the burner *f*. The tube *e* has a flange *n* under which engages the forked end *g* of a bell-crank pivoted on a pin *h*.

The outer end *k* of said bell-crank is placed under control of an eccentric segment *p* attached to the gas-valve *o* in such a manner that the lever *g* with the burner-tube *e* will be in its lowermost position when the gas-valve is, as shown in the drawing, fully opened, and will be raised more and more in proportion to the extent to which the said gas-valve *o* is closed. It is obvious that therefore the distance between the flame and the cooking-pot will be quite automatically varied with the adjustment of the size of the flame.

I claim:

In a gas-cooker, a gas-pipe fitted to the body of the gas-cooker, at the inner end of said gas-pipe a vertical burner-tube, around said burner-tube a second burner-tube telescoping thereon and carrying at its upper end the burner proper, said second burner-tube having at its lower end a flange, a bell-crank pivoted in the body of the gas-cooker, the forked inner end of said bell-crank engaging under said flange, an eccentric segment coupled to the stem of the gas-valve, said eccentric segment acting on the outer end of the said bell-crank.

In testimony whereof we have affixed our signatures in the presence of two witnesses.

HARALD ALBRECHTSEN.

SØREN IVER IVERSEN.

Witnesses:

BELLE HAUSEN,
A. CHRISTOFFERSEN.
